UNITED STATES PATENT OFFICE.

PETER LAWSON, OF MOLINE, ILLINOIS.

WASHING-MACHINE.

SPECIFICATION forming part of Letters Patent No. 321,119, dated June 30, 1885.

Application filed May 19, 1884. (Model.)

To all whom it may concern:

Be it known that I, PETER LAWSON, of Moline, county of Rock Island, and State of Illinois, have invented a new and Improved Washing-Machine, of which the following is a full, clear, and exact description.

The object of my invention is to provide a simple, inexpensive, and efficient machine for washing clothes quickly and thoroughly.

10 The invention consists in the peculiar construction and arrangement of the parts, as hereinafter fully described, and pointed out in the claim.

15 Reference is to be had to the accompanying drawings, forming part of this specification, in which similar letters of reference indicate corresponding parts in both the figures.

20 Figure 1 is a plan view of my improved washing-machine, and Fig. 2 is a vertical sectional elevation of the same, taken on the line *x x*, Fig. 1.

25 The letter A indicates the tub for receiving the clothes and the liquid for washing them. The tub is shown round in form; but it may have any other desired shape.

30 B is a shaft extending across the tub and journaled to rotate in opposite side walls of the tub.

35 On the shaft B is fixed the main washing cylinder or wheel C, which consists of opposite end plates or disks, C', fastened at the ends of a central bar or block, C'', which block may help the end plates support the wheel C on the shaft, as shown. The periphery of the washing-wheel

40 C consists of a series—preferably nine in number—of rubbing-rollers, c, which are journaled to rotate freely and independently in bearings made in the inner sides or faces of the end plates, C'. I make the rollers c in angular cross-sectional form, or with a series of connecting and longitudinally-ranging plane faces—

45 preferably eight in number—which gives the rollers an octagonal form in cross-section; but the number of plane faces may vary as desired.

50 Beneath the wheel C, and at each side of the tub, I pivot at d, to suitable bearing-blocks, e, fixed to the bottom of the tub, the arms D, which extend upward around the wheel C to about the horizontal center of the wheel, and

55 are tied together by the cross board or plate E. In the arms D is journaled the roller F, which

is round in cross-section. This roller F is of such size and is so located in the frame D E that it projects against the rollers c of the wheel C, and its top or the uppermost portion of its periphery is but slightly below the upper face of the board E, which board serves as an apron or guide over which the clothes to be washed are passed between the rollers F c.

55 Springs G, preferably of the coiled form shown, are held to and between the tub-bottom and the board E, and act to force the frame D E and its roller F upward to carry this roller against the rollers c of the wheel C with the requisite force, and permit the roller F to accommodate itself to the varying thickness of the clothes or fabrics being passed between the rollers F c.

60 At H is shown a rubbing board or apron, which is hinged upon pivots h at opposite sides of the tub A, and may be swung on the pivots either up or down, as shown in full and dotted lines, respectively, in Fig. 2, in either of which positions the board H may be used as a rubbing-board on which to soap the clothes.

65 I is a heavy balance-wheel fixed on one end of the wash-wheel shaft B, to give steadiness of motion to the wheel when it is rotated by a suitable crank or handle, J, fixed on the opposite end of the shaft. The board E may have 70 cross cleats or bars f fixed at each end and on the upper side, to prevent sidewise spread of the clothes beyond the ends of the rollers F c by acting as guides to the clothes as they pass into the machine.

75 The operation is as follows: The tub having been supplied with water and soap or other cleansing liquid, the clothes to be washed are held by the left hand and passed over the board E in between the rollers F c, while the crank J 80 is turned by the right hand toward the operator, which draws the clothes quite fully forward into the tub, whereupon the clothes are pulled back again by the left hand, and are then carried forward again by the rollers when

85 the backward pull on the clothes ceases, and these alternate backward and forward movements of the clothes and the rubbing action of the rollers between which they pass act quickly and thoroughly to remove the dirt from the 90 clothes. The rollers F c revolve freely as the clothes are drawn backward or carried for 95 100

ward, so that there is no tearing action on the clothes.

If desired, the machine may be operated by reverse motions of the crank J and wash-wheel 5 to carry the clothes back and forth between the opposing rollers, as will readily be understood.

Having thus described my invention, what I claim as new, and desire to secure by Letters Patent, is—

10 In a washing-machine, the combination, with the tub A and the washing-wheel C, journaled in the tub, and having its periphery formed of

independently-rotating and plane-sided or angular rollers c, of the curved arms D, pivoted at d to the bottom of the tub, and connected together by board E, the pressure-roller F, journaled in the said frame, and the springs G between the free end of the frame and the bottom of the tub, substantially as herein shown and described. 15

PETER LAWSON.
